UNITED STATES PATENT OFFICE.

ROBERT HOOPER, OF BALTIMORE, MARYLAND.

IMPROVEMENT IN CANAL-BOATS.

Specification forming part of Letters Patent No. 117,419, dated July 25, 1871.

To all whom it may concern:

Be it known that I, ROBERT HOOPER, of Baltimore, in the county of Baltimore and State of Maryland, have invented a new and Improved Canal-Boat; and I do hereby declare the following to be a full, clear, and exact description of the same, reference being had to the accompanying drawing making a part of this specification, in which—

Figure 1 is a front elevation, and Fig. 2 is a longitudinal vertical section.

This invention consists in an improvement in the class of canal-boats in which the bow or stern, or both, are so constructed as to form a channel or passage-way for the water. To this end the boat is introverted at the bow and a recess formed for reception of a paddle-wheel, as will be hereinafter more fully described.

Referring to the drawing, A is a canal-boat; *a*, the longitudinal recess at the stern with a sloping upper side; *b*, a chamber, opening from the recess *a* to the deck, for the purpose of re-

ceiving a paddle-wheel for propelling the boat. *c c* are the two parts of the divided bow. *d* are the convex inner sides of the parts *c*. The recess *a* receives water, and the agitation thereof is smothered by the flat bottom of the boat. The sharp edges of the parts *c* cut the water without rolling it off at the sides.

I am well aware it is not new to propel boats by means of a wheel arranged in a recess in the stern, nor to form such recess by extending the sides of the boat backward, leaving the stern rounded under, as usual; but my invention pertains to a different construction and arrangement, which is specified in the following claim:

A boat, A, provided with the recess *a*, with a rounding and sloping upper side in its bow, and the chamber *b* leading into the same, as herein shown and described.

ROBERT HOOPER.
